Howard and Howard

UNITED STATES PATENT OFFICE.

CHARLES RIPPE, OF BRIDGEPORT, CONNECTICUT, ASSIGNOR TO THE BRYANT ELECTRIC COMPANY, OF BRIDGEPORT, CONNECTICUT, A CORPORATION OF CONNECTICUT.

FUSE PLUG.

Application filed June 23, 1927. Serial No. 200,937.

My invention relates to fuse plugs, and my object is to provide a construction which not only so locates the rupture point of the fuse that its integrity can be readily ascertained, but also minimizes the extent of the fuse strip volatilized by the arc on rupture, and causes the current to follow a path which is inimical to the establishment of an arc between the plug contacts.

10 In the accompanying drawings

Fig. 1 is a plan view of a fuse plug in which my invention is embodied in one form; and

15 Figs. 2 and 3 are sections on the lines 2—2 and 3—3, Fig. 1, respectively.

The insulating body 1 of the plug is thimble shaped, affording a central chamber 2 of relatively large capacity, in which the metallic gases, formed on rupture of the fuse strip 3, may expand without danger of injury to 20 the fuse plug. At the bottom of the chamber is a central aperture in the end web of the insulating body, at which the center contact 4 of the plug is secured by means of lugs 5 which pass through the aperture and are upper set within the chamber.

25 On the exterior of the plug body is molded a spiral rib 6, which is engaged by the threads of a screw shell side contact 7. The bottom flange 8 of the latter engages an exterior shoulder 9, while the upper margin of the shell engages the exterior shoulder 10 on the plug body when the shell is screwed fully home on the spiral rib 6.

30 The open end of the thimble is closed by a diaphragm 11 of more or less transparent insulating material, such as mica, held in place by a cap ring 12 resting thereon, having its margin 13 spun beneath the head flange 14 at this end of the plug body.

35 Opening from opposite sides of the fuse chamber 2 at the open or head end of the plug, are bays 15 and 16, with which communicate the outer ends of wells 17 and 18 formed in the side wall of the plug body. These bays 40 15 and 16 are so shaped as to provide ledges 15', 16' and are shallow so that these ledges are relatively close to the outer end of the plug. The well 17 opens at its inner end 19 through the wall of the plug to the screw shell contact 7. The well 18 is inclined to the

45 axis of the plug and opens at its inner end to the lower portion of the chamber 2. The fuse strip 3 extends transversely across the chamber and rests on ledges 15', 16', being 50 thus close to the outer end of the plug and

visible over its full transverse extent. The strip has off-set legs 20, 21 extending into the wells 17, 18 respectively. The leg 20 has its end slightly bowed at 20' to engage the shoulder formed by the opening of well 17 through 55 the body wall. By this the fuse strip is held in place before the metal 22 is flowed in. The shorter leg 20, entering the well 17, is mechanically and electrically connected to the screw shell 7 by metal 22 flowed into the well 17. The longer leg 21 passing down through the well 18 and the lower portion of the chamber 2, is mechanically and electrically connected to the center contact 4 by metal 23 introduced through the chamber.

60 It will be noted that the portion of the fuse strip in which the calibrating recess 24 is formed, is located at the head of the plug and lies adjacent and substantially parallel to the transparent diaphragm 11 through which 65 it may be readily inspected to ascertain whether or not the strip has been ruptured. The legs 20 and 21 of the fuse strip, on the other hand, offset at sharp angles to the calibrated portion of the strip, extend into wells 70 75 80 formed in the insulating body.

On the blowing of the fuse, the strip ruptures at the calibration point 24, and is at least partially volatilized on opposite sides of this point by the heat of the ensuing arc. The 85 path of the fuse strip however, is angular, and in order to follow it the arc must not only pass the chilling ledges at the upper margins of the wells 17 and 18, but must turn abruptly down at each end into these wells. An angular path of this sort is inimical to the maintenance of the arc. If the bays 15 and 16 are 90 filled with insulating material 25 and 26 held in place by the cover 11, the latter adds its chilling effect to that of the ledges. But 95 whether or not such material is used, I have found that the arc does not become established, due to the angularity of the path which it is forced to follow over the chilling barriers of insulation which form the inner 100 walls of the wells 17 and 18.

The construction is economical and efficient. I have found that fuses of relatively large current carrying capacity can be safely used in a plug of the present construction 105 without danger of either establishing an arc between the plug contacts, or of injuring the body of the plug by reason of the heat of the arc, or excessive pressures of the gases formed on rupture.

Modifications in detail will readily occur to those skilled in the art which do not depart from the thoughts which underlie what I claim as my invention.

5 I claim—

1. A fuse plug comprising a thimble-shaped insulating body affording a central chamber, a screw shell side contact mounted on said body, a center contact mounted on 10 said body at the bottom of said chamber, shallow bays opening from substantially opposite sides of said chamber at the outer end thereof and forming ledges, a well opening from one of said bays through the wall of the 15 body to the screw shell, a well opening from the other of said bays through the wall of the body to the inner portion of the chamber, and a fuse strip passing transversely across the chamber at its outer end and resting on said 20 ledges, said strip having one leg offset into the well leading to the screw shell and elec-

trically connected to the latter, and a second leg offset into the well leading to the inner portion of the chamber and passing through said well into said portion of the chamber 25 and there electrically connected to the center contact.

2. A fuse plug comprising a thimble-shaped insulating body affording a central chamber, wells opening through the wall of 30 the body from near the outer end thereof, one well extending to the outside of the body and forming a shoulder where it opens through the outer surface, and one extending to the central chamber, a fuse strip having a trans- 35 verse portion and off-set legs, the end of one leg being slightly bowed to engage the said shoulder to hold the strip in place in the plug.

In testimony whereof I have signed my name to this specification.

CHARLES RIPPE.
